J. Butler,

Steam-Engine Valve-Gear.

No 16,227.

Patented Dec. 16, 1856.

UNITED STATES PATENT OFFICE.

JOHN BUTLER, OF DUNMORE, PENNSYLVANIA.

VALVE-MOTION FOR STEAM-ENGINES.

Specification of Letters Patent No. 16,227, dated December 16, 1856.

To all whom it may concern:

Be it known that I, JOHN BUTLER, of Dunmore, in the county of Luzerne and State of Pennsylvania, have invented a new 5 and Improved Valve-Motion for Steam-Engines; and I do hereby declare that the following is a full, clear, and exact description of the same, reference being had to the accompanying drawing, forming part of this 10 specification, said drawing exhibiting a side view of the principal working parts of a steam-engine with the improved valve-motion applied.

The invention consists in a certain arrangement of eccentrics, rock-shafts, rockers and a yoke or its equivalent, applied to 15 actuate a slide valve so as to make it serve both as an induction and eduction valve and a variable cut off.

20 To enable others skilled in the art to make and use my invention, I will proceed to describe its construction and operation.

M, is the main framing of the engine, A, is the steam cylinder, B, is the valve seat, 25 and C, the slide valve, which need not differ from the slide valves generally used. The stem *a*, of this slide valve is made long and furnished with a yoke-frame *b*, and has stationary guides *p*, *p'*, provided for it.

30 D, is a light framing erected on the main frame M, of the engine to carry the bearings for two rock shafts E and F, which are arranged parallel with each other one below the other. The rockshaft E, is furnished 35 with an arm *e*, which connects with the rod G', of an eccentric G, on the crank shaft S, of the engine, and the rockshaft F, is furnished with an arm *f*, which connects with the rod H', of another eccentric H, on the 40 crank shaft.

The rockshaft E, is furnished with a rocker *g*, which carries a stud *g'*, which plays within the yoke frame *b*. The yoke frame is of such width that as the rocker is 45 moved by the action of the eccentric G, the stud *g'*, will make the greater part of its movement in either direction within the yoke frame without touching it, and then striking one end of it, will move it and the 50 valve rod far enough for the valve to open the port *s*, or *s'*, to admit steam to the cylinder, said movement thus taking place during a very small portion of the revolution of the crank shaft, and the eccentric G, being set

in such relation to the crank that the said 55 motion commences as the piston terminates its stroke, and is completed shortly after the commencement of the return stroke.

The rock shaft F, is furnished with a rocker *h*, carrying a stud *h'*, which, by the 60 action of the eccentric H, is caused to play within the yoke frame *b*, in a similar manner to the stud *g'*, of the rocker *g*. This stud when it strikes the yoke moves the valve far enough back from the position to which 65 it has been previously moved by the stud *g'*, connected with the other rockshaft and eccentric, to cover the port *s*, or *s'*, and cut off the steam from the cylinder, but not far enough to open the opposite port which remains closed until the rocker *g* and its stud 70 *g'*, operate on the yoke frame.

The operation proceeds in the above manner, the eccentric G, rockshaft E, rocker *g*, and stud *g'* operating on the yoke to move 75 the valve in either direction to open one of the ports to admit steam to one side of the piston, and the other eccentric H, rockshaft F, rocker *h*, and stud *h'*, operating on it to move the valve back again only far enough 80 to cut off the steam, leaving the movement which is necessary to open the other port to admit steam on the other side of the piston to be completed by the eccentric G, rockshaft E, rocker *g*, and stud *g'*. By the above- 85 described operation, a very quick movement is given to the valve in opening and closing and the ports are allowed to remain wide open during as much of the stroke as desired.

The variation in the time of cutting off 90 the steam is to be effected generally, by moving the eccentric H farther forward or backward, relatively to the crank on the shaft S. A slight variation may however be effected by shifting the stud in the arm *f*, 95 on which the hook of the eccentric rod H', catches, nearer to or farther from the rock-shaft F, in a slot provided for the purpose—thereby varying the length of stroke of the stud *h'*.

Instead of using a yoke frame *b* the valve rod may be furnished with lugs corresponding in position with the ends of the yoke frame, the studs *g'*, and *h'*, of the rockers to play between said lugs in the same manner as within the yoke frame. This is an 100 equivalent of the yoke frame.

I do not claim the use of two eccentrics to

give the valve two distinct movements to admit and cut off the steam. But

What I claim as my invention and desire to secure by Letters Patent, is—

5 The arrangement of the two rockshafts E, F, with their rockers operating upon a yoke b, or its equivalent, attached to the

valve stem said rockshafts deriving motion from separate eccentrics and the whole operating substantially as herein described.

JOHN BUTLER.
